UNITED STATES PATENT OFFICE

ROLLO F. WALTERS, OF DETROIT, MICHIGAN, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

UPHOLSTERY INSTALLATION AND FASTENER ELEMENT FOR USE THEREWITH

Application filed July 24, 1924. Serial No. 727,956.

This invention aims to provide an improved upholstery installation and improved fastening devices primarily useful in such installations.

5 In the drawing, which illustrates a preferred embodiment of my invention:—

Figure 1 is an inside view of an automobile door showing the framework and various sockets as used in the preferred form of my 10 device;

Fig. 2 is a front elevation of the upholstery installation with the outside covering removed to show the attachment of the studs thereto;

15 Fig. 3 is a section on the line 3—3 of Fig. 2, showing the upholstered part secured to the framework by separable fastener elements;

Fig. 4 is a section on the line 4—4 of Fig. 1, showing the upholstered part secured to the 20 framework by separable fastener elements;

Fig. 5 is a section on the line 5—5 of Fig. 1;

Fig. 6 is a plan and end elevation of a corner stud and reinforcing member;

25 Fig. 7 is a plan view of another reinforcing member particularly fitted for straight edges;

Fig. 8 is an edge view of the reinforcing member as shown in Fig. 7;

Fig. 9 is a plan view of the fastener stud 30 with a round base shown in Figs. 4 and 5; and

Fig. 10 is a side elevation of the fastener stud shown in Fig. 9.

Referring to the drawing, I have shown an 35 upholstery installation (Fig. 2) including an upholstered part for application to a frame (Fig. 1). The upholstered part is provided with a plurality of reinforcing strips of varying shapes, shown in Figs. 3, 6, 7 and 8, which are clenched over its edges to protect them 40 from becoming damaged and also to stiffen the upholstered part adjacent the edges, thus making it more durable than it would be without the reinforcing strips.

The part to be covered by the upholstery, 45 herein shown as a door, may be of wood or metal, or a combination of the two, and provided with stud-receiving apertures for reception of heads of studs. Where the supporting frame is of wood, separate sockets may be 50 attached thereto. Where it is of metal, por-

tions thereof forming the face to which the upholstery is to be applied, may have holes punched or drilled therein so that stud-receiving apertures are presented in the metal, thereby eliminating the necessity for separate 55 sockets.

In Fig. 1, I have shown a wooden frame 1, having a metal covering 2 for the outside of the door. This covering extends over the edges of the door and onto the adjacent face 60 of the wooden frame 1, where it presents, at various points, a plurality of flange portions 3 in which are punched or drilled one or several stud-receiving apertures according to the length of the flange. These flanges 3 may 65 be located at different points at the inside of the door and in an all metal door may extend completely around the inside of the door frame.

Referring now to the composite wood and 70 metal door illustrated, in some instances, where the metal does not extend over the wooden frame 1, as at the lower rounded corners of the door (Fig. 1), separate sockets 5 are secured to the wooden frame by a plurality of attaching prongs.

The upholstered part comprises a relatively stiff backing 7 of cardboard or the like having a plurality of holes 8 therethrough adjacent the periphery of the backing. 80 Through these holes protrude the heads 10 of studs for engagement with the stud-receiving apertures 4 in the door.

Each stud comprises a base 9 (Fig. 6), 9a (Fig. 9), 9b (Fig. 7) or 9c (Fig. 9) according to its shape, a head 10 and a neck 11. The head is permitted to contract and expand when engaging with or disengaging from a stud-receiving aperture 4 by reason of a plurality of longitudinal slots 12, which 90 extend from the outer end of the head preferably to the base of the stud, as illustrated.

By locating the base of the stud at the opposite side of the backing from the side where the head 10 of the stud protrudes, I am able 95 to avail of the thickness of the backing to provide additional length to the stud without increasing the distance which the head of the stud protrudes. This additional length enables me in the type of stud shown, 100

to provide longer slots, thereby increasing the resiliency of the stud head, and, even more important, so locates the base of the stud that it back-supports the fiber or cardboard backing when the installation is being removed from the support which it covers.

Separate bases may be supplied for individual studs, or several studs may project from a single strip, which then provide a common base for all the studs formed thereon.

The studs, whether individual or combined in a strip, may be secured to the backing 7 by prongs 13 penetrating the backing and extending in the same direction as the stud heads, being clenched over that face of the backing which lies against the socket. These prongs have little to do after the upholstery installation is completed, but are of use prior to completion thereof and particularly during the entrance of the stud into the socket, at which time, unless the engaging pressure is applied to or in line with the base of the stud, the whole engaging force must be borne by these prongs 13.

The prongs are preferably bent inwardly and downwardly against the cardboard, so that the base of the stud may form a support for the backing 7, while the prongs 13 are being clenched against the backing. By attaching the studs in the manner just described, a clench plate is not necessary because all of the strain exerted upon the stud through the cardboard backing is exerted upon the base of the stud instead of the prongs 13.

Also this method of attachment is desirable because the amount of material which projects beyond the surface of the backing is reduced to a minimum, thus allowing the flexible covering 6 to lie smoothly against the surface of the backing.

In Fig. 2, I have shown a plurality of reinforcing strips which have heretofore been called the base portions of the studs. Where the bases of the studs are of varying shapes, as illustrated, to fit the different parts of the backing 7, they may also provide a means by which the upholstered portion may be greatly stiffened at the points where the upholstery is most likely to gap or be pulled free from the door. They also protect and stiffen the edges of the upholstery and keep the edges pressed tightly against the framework when the studs are engaged in the stud-receiving apertures 4.

These base portions or reinforcing strips may be of suitable shape, triangular 9 for sharp corners, as shown in Figs. 2 and 6, rounded for round corners 9a, as shown in Fig. 2, oblong 9b, as shown in Figs. 2 and 7, and just plain round 9c as shown in Figs. 2 and 9.

When the base portions are used as reinforcing strips, as shown in Figs. 2, 3, 6 and 7, the flaps 15 (Fig. 6) or 15a (Fig. 7) may

be bent on the dotted lines 16, over the edge of the cardboard and clenched against the opposite side thereof to insure a secure fastening of the base portion to the cardboard, the prongs 13 preventing any lateral shifting thereof.

After the studs have been secured to the backing, the outer covering 6 of flexible material is placed over the backing on that side where the bases of the studs are exposed and is secured to the backing by stretching it over the edges thereof and onto the adjacent face where it is secured by pasting, or in any suitable manner. Thus the cardboard and the bases of the studs are concealed from view and the installation presents a neat and finished appearance.

In wooden frames, the drilled recesses 14 are provided behind the stud-receiving apertures where the wood might otherwise obstruct entrance of the head of the stud.

The smallest diameter of the neck of each stud is preferably so located that the head 10 of the stud is sloped where it engages the socket, and the diameter at this point of engagement is preferably such that the stud heads will be slightly contracted when the upholstered part contacts with the metal part of the door. The stud, therefore, by reason of the slope, constantly exerts a pull on the upholstered part which keeps the edges of the upholstered part tightly pressed against the adjacent face of the part to which it is attached. Thus an installation is provided which presents no gaping edges.

While I have shown and described my invention in connection with the application of an upholstered part to an automobile door panel, it will be understood that it is of use in connection with upholstery installations generally, whether padded or not. In a companion application, filed herewith, is shown and claimed a somewhat similar installation wherein the studs and their bases are carried by, but shiftable relative to, base pieces attached to the backing. Some of the features herein claimed are useful with studs which are shiftable. The specific disclosures of the description and drawing of this application are for purposes of clarification and not for purposes of limitation, my invention being best defined in the appended claims.

I claim:

1. A reinforcing fastener strip for an upholstered part comprising a single sheet of metal presenting fastening means for engagement with cooperating separable fastening means located upon the part to be covered by the upholstered part, a plurality of prongs for securing the reinforcing strip to the backing of the upholstered part and a flap portion adapted to be bent over the edge of the backing and against the opposite face thereof, thereby to reinforce the edge of the backing.

2. A reinforcing fastener strip for an upholstered part comprising a single sheet of metal presenting fastening means for engagement with cooperating separable fastening means located upon the part to be covered by the upholstered part, a plurality of prongs for securing the reinforcing strip to the backing of the upholstered part and a plurality of flap portions adapted to be bent over the edges of the backing to reinforce the backing adjacent the edges thereof.

3. A reinforcing fastener element comprising a strip of sheet metal of substantial area having a plurality of integral stud heads pressed therefrom and a plurality of integral bendable attaching elements formed from said strip and extending therefrom in the same direction as said stud heads for attaching the strip to a support.

20 4. An upholstered part including a backing, a covering for one side of said backing and a plurality of studs for detachably securing said upholstered part to a frame, said studs having a base between said backing and said covering, said base presenting a portion which is crimped over the edge of the backing and against the opposite face thereof to secure said base in position upon said backing and to reinforce the edge of said installation, 30 said crimped-over portion being concealed by an overfolded edge of said covering.

5. An upholstered part including a generally stiff backing, a reinforcing strip secured to the edge of said backing to protect and stiffen said edge, and a stud member formed from the material of said strip and presented for engagement with a suitable socket presented by a part to which the upholstered part is to be secured.

40 6. An upholstered part including a generally stiff backing, a reinforcing strip, means formed integral with said strip for securing the strip to said backing and a plurality of stud members formed integral with said strip, said stud members passing through said backing and exposed at the opposite side thereof and a flexible covering for concealing said reinforcing strip and for providing a finish to one face of said backing.

50 In witness whereof, I have signed my name to this specification.

ROLLO F. WALTERS.
